No. 703,428.

Patented July 1, 1902.

J. KNOCHE.
WASHING MACHINE.

(Application filed May 5, 1900.)

(No Model.)

UNITED STATES PATENT OFFICE.

JOHN KNOCHE, OF CINCINNATI, OHIO.

WASHING-MACHINE.

SPECIFICATION forming part of Letters Patent No. 703,428, dated July 1, 1902.

Application filed May 5, 1900. Serial No. 15,590. (No model.)

To all whom it may concern:

Be it known that I, JOHN KNOCHE, a citizen of the United States of America, and a resident of Cincinnati, in the county of Hamilton and State of Ohio, have invented certain new and useful Improvements in Washing-Machines, of which the following is a specification.

The object of my invention is a machine which separates the dirt from soiled clothes without subjecting them to rubbing by suction produced by a series of cups arranged upon a rocker, in which the parts are few and simple in construction and readily taken apart.

Referring to the drawings, in which like parts are indicated by similar reference-letters wherever they occur throughout the various views, Figure 1 is a view, partly in side elevation and partly in longitudinal vertical section, of a machine embodying my invention, the tub being shown in longitudinal section and the rocker partly in section and partly in side elevation and its actuating-shaft in central section. Fig. 2 is a view in side elevation of the same, the rocker being shown in dotted lines in the position reverse to that shown in Fig. 1 and the latch shown in full lines engaging the actuating-shaft, and in dotted lines swung back, releasing the shaft, so that it may be lifted from its bearings. Fig. 3 is an inverted plan view of the rocker, showing its series of cups. Fig. 4 is a central transverse sectional view showing a modified form of rocker in its lowest or horizontal position. Fig. 5 is a detail plan view of a portion of the modified form of rocker, showing the pair of rods which engage the actuating-rod to impart the motion to the rocker. Fig. 6 is a detail sectional view of the rocker, taken upon line $\alpha-\alpha$ of Fig. 4. Fig. 7 is a detail view of a portion of the rocker of Figs. 1 and 2, showing a portion of one of the slots in the top thereof, the horizontal strip covering it, and the pin for passing down through the strip into the side of the rocker.

Referring to the parts, the tub A is a rectangular box supported upon standards a . Rocker B is likewise rectangular in shape and of the same dimensions as the interior of the tub. It consists of a series of parallel

vertical longitudinal members b , secured to the ends b^1 , b^2 of the rocker and between which are secured a series of vertical transverse members b^3 , forming cups b^4 . In the form shown in Figs. 1 to 3, inclusive, horizontal transverse strips b^5 are secured upon the longitudinal members b above transverse members b^3 , leaving slots b^6 between them. 55 Covering the slots and resting upon strips b^5 are horizontal strips b^7 , through the ends of which pins b^8 pass down into the sides of the rocker, so that when the rocker descends the pressure of the air in the cups may raise 60 strips b^7 and allow them to pass out through the slots b^6 , and that when the rocker ascends strips b^7 are held down upon the slots by the air on top of them. Secured to the strips b^5 are parallel bars b^9 , which have notches at 70 points above strips b^7 or have a secondary strips placed between them and strips b^5 to allow strips b^7 to have a vertical movement imparted to them and upon which rests plate C, as shown in Fig. 1, or upon which rests 75 the base b^{10} , to which is secured the plate C, formed integral with which or secured to which is the pair of parallel rods c , c' , which engage the actuating-shaft D.

In the form of rocker shown in Figs. 4 and 80 6 the horizontal transverse strips b^{11} are secured upon the vertical longitudinal members b , so that slots b^{12} between them come above the vertical transverse members b^3 , and the strips b^{13} , covering the slots, are notched 85 at b^{14} beneath the bars b^9 , which are likewise notched, so that strips b^{13} may be raised, as shown in Fig. 6, for the escape of the air from the cups when the rocker descends. Between the ends of strips b^{11} and resting upon the 90 sides b of the rocker are blocks b^{15} to prevent the entrance of air into the cups when the valves are closed. In the form shown in Figs. 1 to 3 narrow longitudinal strips b^{16} rest upon top of sides b , as shown in Fig. 7, and extend 95 their entire length for the same purpose.

Shaft D is journaled at its ends in semi-circular notches in the sides of the tub A, being retained therein at one side by passing through a perforation in metal plate a' , secured to the side of the tub, and at the other by a latch a^2 , pivoted to the tub, the shaft being further steadied in its bearings by its collars d , d' bearing against the interior walls

of the sides of the tub. Upon one end of the shaft is a crank d^2 . At its center shaft D is bent into a U-shaped curve d^3 , which fits in between and bears against rods $c c'$ to rock rocker B when crank d^2 is rotated, the rocker falling down to its lowest or horizontal position when the curve d^3 is in a vertical position either at the highest or the lowest point of its path and being tilted at its greatest angle to the horizontal either in one direction or the opposite when the curve d^3 is in its horizontal position. As is seen, the rocker may by this mechanism have a very rapid motion imparted to it, thereby subjecting the clothes to a thorough pounding to loosen the dirt, and that when the rocker ascends the suction in the cups causes the water and soap to ooze through and take the loosened dirt out of the clothes and that the only motion the operator needs to make is to turn the crank.

To remove the rocker from the tub, latch a^2 is thrown back out of engagement with shaft D, as shown in dotted lines, Fig. 2, brace-bar c^4 , which is pivoted on top of rod c to fit down on rod c' to hold the pair firm, is thrown back, as shown in dotted line, Fig. 1, and the shaft lifted out of its bearings, leaving the rocker free to be lifted from the tub.

What I claim is—

In a washing-machine the combination of a tub, a rocker therein with its ends abutting against the ends of the tub and carrying a pair of parallel upwardly-projecting rods, and a shaft journaled in the sides of the tub and having a U-shaped curve to fit between the rods, substantially as shown and described.

JOHN KNOCHE.
